Inventor
Gatley Seymour & Earle

UNITED STATES PATENT OFFICE.

HARRY TAYLOR TURNOR, OF ROEWEN, ENGLAND, ASSIGNOR TO JAMES R. McCLELLAND, OF NEW HAVEN, CONNECTICUT.

TOY.

SPECIFICATION forming part of Letters Patent No. 787,062, dated April 11, 1905.

Application filed November 7, 1904. Serial No. 231,709.

To all whom it may concern:

Be it known that I, HARRY TAYLOR TURNOR, a subject of the King of Great Britain, and a resident of Roewen, England, have invented 5 a new and useful Improvement in Toys; and I do hereby declare the following, when taken in connection with the accompanying drawings and the letters of reference marked thereon, to be a full, clear, and exact description of 10 the same, and which said drawings constitute part of this specification, and represent, in—

Figure 1, a perspective view of a toy constructed in accordance with my invention; Fig. 2, a side view with the case in section, 15 showing the inner tube and cords arranged thereon; Fig. 3, a longitudinal section with the slide in its retired position; Fig. 4, a similar view with the slide in its forward position and the point projecting outward through the 20 end of the case.

This invention relates to an improvement in toys, and particularly to those of so-called "trick-like" character, the object of the invention being to produce a device by which 25 the unwary operator may be induced to so manipulate the device as to cause a pin-point to be thrust into his finger; and the invention consists in the construction as hereinafter described, and particularly recited in the claims.

30 In carrying out my invention I employ a tubular case or shell 2, of paper or other suitable material, closed at opposite ends by plugs 3. These plugs have longitudinal openings 4, in which a tube 5 is secured, the tube 35 being considerably smaller in diameter than the case 2. In the outer face of the plugs are recesses 6, in which paper disks 7 are inserted, the paper disk having central openings 8. In opposite sides of the case are openings 9, 40 10, and 11. Near one end of the tube 5 is a transverse bar 12, and near the opposite end of the tube 5 is another transverse bar 13. Within the tube is a slide 14, carrying a long sharp-pointed pin 15, projecting outward from 45 one end. Extending through the opening 10 in the case 2 and into the tube 5 is a cord 16, which passes under the bar 12, forward over

the bar 13, and is secured to the slide 14. Extending into the case through the opening 11 is a cord 17, which passes over the bar 12 into 50 engagement with the rear end of the slide 14. Preferably these cords 16 and 17 are differentiated in color—that is, the cord 16 may be white and the cord 17 may be black. Passing through the opening 9 and wound upon 55 the tube 5 are cords 18, the cords 16, 17, and 18 being provided with heads or buttons 19, and the cords 18 have their ends differently colored, so that the end of the cord passing into the case from the tube is of different 60 color from the end of the same cord which passes out through the bottom of the case. The cords 18 may be drawn back and forth at will and appear to change color as they are drawn through the case. In drawing the 65 cords 16, however, the slide 14 is drawn forward, so as to project the pin 15 through the opening 8 in the plug 3, and so that it will prick the finger of the holder. Drawing the 70 cord 16 outward draws the cord 17 inward, and as the cord 17 is directly below the cord 16 it appears that as the cord 16 is drawn upward it changes color. By drawing the cord 17 downward the slide 14 is drawn rearward and by this movement draws the cord 16 inward. The cords 18 may be drawn back and 75 forth through the case, each without affecting the other, and the number of them may be increased or diminished, as desired. As herein shown, I employ three of such independently-operating cords.

Having fully described my invention, what I claim as new, and desire to secure by Letters Patent, is—

1. A toy comprising a case having ends, an 85 internal tube mounted in said ends, openings in opposite sides of the case through which cords may pass, a slide in said tube and carrying a point, cords extending through the opposite sides of the case into the tube and 90 connected to the slide to move said slide back and forth, substantially as described.

2. A toy comprising a case, a longitudinally-arranged tube therein, cords extending

through the case and around said tube, trans-
verse bars extending through said tube, a slide
in said tube and carrying a point, and cords
extending through said case into said tube over
5 the bars therein and into engagement with said
slide, whereby said slide may be moved back
and forth, substantially as described.

In testimony whereof I have signed this
specification in the presence of two subscriv-
ing witnesses.

HARRY TAYLOR TURNOR.
